DESIGN FOR A CABINET FOR AUTOMATIC PHOTOGRAPHIC APPARATUS

Philip S. Allen, Long Beach, Calif.

Application August 9, 1947, Serial No. 140,788

Term of patent 14 years

(Cl. D61—1)

To all whom it may concern:

Be it known that I, Philip S. Allen, a citizen of the United States, residing at Long Beach, in the county of Los Angeles, State of California, have invented a new, original, and ornamental Design for a Cabinet for Automatic Photographic Apparatus, of which the following is a specification, reference being had to the accompanying drawings, forming a part thereof, and in which:

Fig. 1 is a perspective view of the cabinet looking at one end and side thereof, and showing my new design.

Fig. 2 is likewise a perspective view of the cabinet, but looking from the other end and side thereof.

I claim:

The ornamental design for a cabinet for automatic photographic apparatus, as shown.

PHILIP S. ALLEN.
